ABSTRACT

A piston-cylinder drive structure particularly for use in actuating electric switchgear apparatus comprises a cylinder into which explosion gases are admitted for actuating a piston located in the cylinder. Rather than having a uniform cross-sectional area, the cross-section of the cylinder is progressively increased in the direction of piston travel and the piston includes means for effecting a like increase in its cross-sectional area as it is actuated and maintains its engagement with the cylinder wall. The result is a more favorable force-travel characteristic resulting in practically a constant pressure throughout the piston travel for the switchgear drive notwithstanding a progressively decreasing gas pressure concurrent with a progressively increasing volume within the cylinder.

1 Claim, 2 Drawing Figures

FIG.1

FIG.2

EXPLOSION GAS OPERATED PISTON-CYLINDER STRUCTURE

This invention relates to an improvement in a drive apparatus of the type in which a piston is displaced in a cylinder by explosion of a charge, in particular for operating electrical switchgear.

Electrical switching devices with so-called explosion drives are known where the drive is of such a form that a drive piston is located in a cylinder of circular cross-section such as described in German specification published June 15, 1972, for example. Drives of this kind exhibit an unfavorable displacement characteristic, accompanied by high material stresses, because owing to the very high combustion rate of the propellant charge the duration of combustion is much shorter than the mechanical travel time suitable and acceptable for most electrical switching devices. Furthermore, if the size of the propellant charge is within economically tolerable limits the volume of gas resulting from the explosion is relatively small, and therefore, owing to the increase in volume of the drive chamber as the piston is displaced, the pressure of the gases in the chamber falls off very rapidly during the mechanical movement.

The principal object of the invention is to provide a solution such that the pressure and piston displacement are better matched to each other, resulting in a more favorable force/travel characteristic, e.g., practically constant pressure throughout the piston travel, for the drive apparatus described above. This objective is achieved in that the cylinder chamber is of rectangular cross-section, the cross-section area increasing progressively in the direction of piston travel, and that the piston which likewise increases in area incorporates means whereby a seal, at least quasi-leakproof, is maintained between the piston and the inner cylinder wall during the mechanical movement.

A preferred embodiment of the invention is illustrated in the accompanying drawing, in which:

FIG. 1 is a sectional elevation of the drive apparatus, and

FIG. 2 is a cross-section through the apparatus at line A—A and viewed in the direction of the arrows.

With reference now to FIG. 1, the drive piston 1 is located in cylinder chamber 2. The latter is of rectangular cross-section increasing progressively in area in the direction of piston displacement. For this purpose a conical housing 3 contains four segment-shaped elements 2a to 2d. The cylinder chamber 2 thus has two wedge-shaped and two parallel bounding surfaces, the former being formed by elements 2c, 2d and the latter by elements 2a, 2b. The housing 3 is enclosed at one end by a flanged cover 4 through which the piston rod 1a of piston 1 passes. At the opposite end of the housing is an opening 5 through which the explosion gases are admitted. Connected to the opening 5 is a combustion chamber, not described in further detail, with an ignition device and supply of explosion propellant. The head of piston 1 subjected to the explosion gases and which is expandable in area when moving in the driven direction comprises two flaps 6 which are pivoted about studs 7 to establish the increasing cross-sectional area character of the piston that matches the increasing cross-sectional area of the explosion chamber. In the lower, fully withdrawn, end position, i.e., the starting position of the piston, the flaps 6 are pressed at their lower rounded ends by spring 8 into sealing engagement against elements 2c, 2d. The flaps 6 are sealed

along their sides relative to elements 2a, 2b by pieces 10, e.g., of steel, inserted in corresponding slots. To press the pieces 10 against the parallel surfaces of elements 2a, 2b, spring devices, e.g., corrugated spring strips 9, can be inserted between pieces 10 and the base of the slots, as shown in more detail in FIG. 2. At the top in the vicinity of the pivot axes the flaps 6 are sealed relative to one another by a steel element 11 which fills the intervening space.

The explosion gases created when a propellant charge is ignited are fed through the opening 5 and displace the piston 1 to its upper extreme position, indicated by the broken line. In this manner the electrical switching device, connected in known fashion with the piston rod 1a and not further described, is moved in the desired direction. During this movement the flaps 6 are pressed also by the gas pressure against elements 2c, 2d in addition to the force of spring 8. At the same time this has the effect of progressively increasing the effective piston surface area, and as a result the driving force remains practically constant, despite the decreasing pressure owing to the increasing volume of the chamber. The discharge ports 12 in the segment shaped elements 2a, 2b open at or shortly before the upper end position as they are partly uncovered by the expandable piston head as shown by the broken line position of these flaps in FIG. 1 so that the explosion gases can escape through ports 12 and the openings 13 in flange cover 4. If the switching device is also to be driven in the opposite direction by drive apparatus of the kind proposed, one such apparatus is provided for each direction, the one being returned to its starting position by the other.

I claim:

1. A piston-cylinder drive structure for use in actuating electric switchgear apparatus comprising a cylinder including a conical housing containing two pairs of oppositely disposed segment-shaped elements establishing a working chamber for explosion gases admitted through an inlet at the smaller end of the housing, a first pair of said segment-shaped elements establishing a pair of oppositely disposed wedge-shaped bounding surfaces and a second pair of said segment-shaped elements establishing a second pair of oppositely disposed parallel bounding surfaces which together establish a working chamber having a rectangular cross-section and whose area progressively increases in the drive direction of the piston travel from the explosion gas inlet end, a drive piston within said working chamber, said drive piston including a piston rod extending through the larger end of said housing and having an area-expandable head slidable in contact with the said bounding surfaces of said chamber from the smaller to the larger area end in response to the pressure of the explosion gases, said piston head comprising two pivotally mounted flaps and spring means cooperable therewith and which serve to maintain said flaps in sealing contact with said pair of wedge-shaped bounding surfaces, the sides of said pivotally mounted flaps in contact with said second pair of oppositely disposed parallel bounding surfaces including slots containing spring-loaded sealing strips which function as piston seals with respect to said parallel bounding surfaces, and at least one of said second pair of segment-shaped elements including a port for discharge of spent gases therethrough into the larger end of said housing and thence through an escape opening therein into the surrounding atmosphere, said spent gas discharge port being uncovered by said piston when it reaches the end of its working stroke.
